[57]

ABSTRACT

A plurality of generally disclike elements are unitarily arranged in stacked, face contacting relation within a cartridge. The projectile element edges are formed into a set of teeth or projections for cooperation with similarly dimensioned toothed tracks to produce element rotation for movement along guide grooves extending longitudinally within a gun barrel. As a further aspect, the guide grooves are fanned out a predetermined amount in the region immediately adjacent the muzzle to produce a prescribed element dispersion.

MULTI-SECTION PROJECTILE AND MEANS FOR FIRING THE SAME

FIELD OF THE INVENTION

The present invention relates generally to a multisec-
tion projectile and gun means for firing the same, and,
more particularly, to such a projectile including a num-
ber of separable elements unitarily arranged in a car-
tridge and fired by a single propellant charge.

OBJECTS AND SUMMARY

It is, therefore, a primary object of this invention to
provide an improved multi-part projectile which on fir-
ing presents an extended bandlike pattern.

Another object is the provision of a multi-section
projectile, the parts of which on firing are each im-
parted with rotative as well as translational motion im-
proving dynamic stability.

A further object is the provision of a multi-part pro-
jectile, the parts of which closely fit within grooves in
a gun barrel so that during initial firing stages an effec-
tive gas seal is maintained between the projectile and
gun barrel.

A still further object is the provision of gun barrel
means for the multi-section projectile described in the
above objects in which guiding grooves direct the pro-
jectile sections along respective paths producing a
wedgelike dispersal pattern at a prescribed distance.

In accordance with the practice of the present inven-
tion the multi-section projectile includes a plurality of
generally disclike elements unitarily arranged in
stacked, face contacting relation within a cartridge.
The projectile element edges are formed into a set of
teeth or projections which cooperate with similarly di-
mensioned toothed tracks for rotative movement along
guide grooves extending longitudinally within a gun
barrel. The cartridge is located within the gun chamber
with the element stack extending transverse of the bar-
rel and the elements individually edge-aligned to the
guide grooves. As a further aspect, the guide grooves
are fanned out a predetermined amount in the region
immediately adjacent the muzzle to produce a pre-
scribed element dispersion.

DESCRIPTION OF THE DRAWINGS

FIG. 1 is a perspective view of a cartridge including
the multi-section projectile or bullet of the present in-
vention.

FIG. 2 is a perspective view of one element of the
multi-section projectile or bullet of FIG. 1.

FIG. 3 is a sectional, elevational view taken along line
3-3 of the cartridge in FIG. 1.

FIG. 4 is an elevational view in section of the car-
tridge of FIG. 1 within the gun chamber also depicting
movement of a projectile element along the gun barrel.

FIG. 5 is a transverse sectional view taken along line
5-5 in FIG. 4.

FIG. 6 is a plan, sectional view of the barrel end por-
tion especially adapted for use in propulsion of the mul-
ti-section projectile of this invention.

DESCRIPTION OF A PREFERRED EMBODIMENT

Turning now to the drawings, and particularly to
FIGS. 1 and 3, a cartridge assembly 10 is seen to in-
clude a hollow cartridge case 11 having a primer as-
sembly 12 in its closed end wall, a quantity of propel-

lant 13, a multi-section bullet or projectile 14 to be
more fully described, and an end wad 15. The cartridge
case 11 can be made of, optionally, brass, steel or alu-
minum and is of conventional construction other than
5 having a generally rectangular cross-section for accom-
modating the multi-section projectile. The primer may
be any one of a number of different commercially or
militarily available primers for small arms. Similarly,
the propellant 13 may be selected from any number of
10 known substances, and the wad 15 typically may be
made of paraffin wax, or the like.

The multi-section projectile 14 includes a plurality of
identical circular disclike elements 16, the peripheries
of which are formed into a continuous set of equally
15 spaced teeth 17. The elements have their edge margins
beveled to a substantial knife edge 18 as seen best in
FIGS. 2 and 5.

The elements 16 may be constructed of any of the
usual bullet materials, e.g., lead, steel, copper, ura-
nium, tungsten, or any other metal having sufficient
20 strength and rigidity to withstand propulsion. Evalu-
ation tests indicate that depleted uranium is a near opti-
mum material from which to construct elements 16.
Tungsten alloys closely follow with steel next.

25 In assembly after the propellant is added, the ele-
ments 16 are stacked in side by side, face contacting
relation and inserted into the open end of the cartridge
case 11 with the edges facing outwardly. The case is
30 crimped as at 19 to secure the projectile elements
therewithin and to align the element teeth transversely
of the case. End wad 15 then closes the outer case
opening.

As shown best in FIG. 4, the gun chamber 20 is
35 formed to receive the cartridge 10 in a tight fitting rela-
tion. The upper inner surfaces of the barrel 21 includes
a first set of longitudinally extending grooves 22 of
transverse dimension and mutual spacing identical to
40 that of the elements 16 forming the projectile 14. A
second set 23 of similar longitudinal grooves is pro-
vided along the lower inside barrel surface, the grooves
of the second set being aligned with and in vertical reg-
istry with the grooves 22.

The leading end of the cartridge 10 abuts against a
45 shoulder 24 defining the beginning of the gun barrel,
and also, the beginning of the two sets 22 and 23 of
guide grooves. For a short distance along the lower
grooves from the shoulder 24, there are provided
50 toothlike projections 25 of dimensions for cooperative
action with the bullet element teeth 17 in a way that
will be described.

For satisfactory operation there are also required ad-
ditional apparatus such as a trigger mechanism, stock
or grip, magazine, extraction means and sight, for ex-
55 ample. All of these may be of conventional construc-
tion and do not form a part of the present invention.

When the cartridge 10 in the chamber 20 is fired, the
elements 16 move into the chamber with their upper
edges being received in the upper set of grooves 22
(FIG. 4). Also, as the elements 16 leave the cartridge
60 case, rotation is initiated by the crimped portion 19 re-
tarding the elements lower edges. On the elements
leaving the cartridge case, the lower element edge teeth
engage the projections 25 which continues the rotative
65 motion for each element as it simultaneously moves
outwardly along the gun barrel. During such movement
along the barrel the grooves 22 and 23 maintain the el-
ement upright throughout the barrel length so that they

are emitted from the muzzle substantially in a line with their edges facing the target. In addition, since the grooves 22 are 23 are formed to closely match the beveled element edges and teeth a gas seal is achieved enhancing propulsion.

An alternate form of gun barrel is that shown in FIG. 6 which obtains a wider dispersion of the bullet elements than that achieved by the first described embodiment. Thus, whereas in the first barrel form the grooves are straight-line throughout the entire barrel length, in this alternate version the grooves in the region 26 immediately adjacent the muzzle curve away from each other or fan out a slight amount. As the multi-section bullet reaches the region 26, the propellant gases leak past the elements just before they leave the muzzle. 15 Moreover, since the guide grooves diverge, this effects a dispersal of the elements.

Illustrative of a practical embodiment for use in a hand-held or shoulder-fired weapon, each bullet element 16 comprises a disclike body member 0.25 inches 20 in diameter and 0.025 inches thick with 8-10 teeth. Fifty elements stacked in side-by-side relation form a multi-section bullet 1.25 inches by 0.25 inches. It has been found that vertical dispersion, i.e., measured transversely of the element stack, was approximately 1 foot at a distance of 100 feet down range, or substantially 0.5°. Lateral dispersion, on the other hand, at the same distance down range was 5 to 10 feet, or 3° to 6°. The disc elements spread out generally uniformly and retain their edge forward orientation during flight. In 30 addition, depending on the initial yaw position, some precession of the spinning elements occurs producing a wedge-shaped pattern which may be considered lethal anywhere within the range of 0-300 feet.

There is provided in accordance with the practice of 35 this invention a multi-section projectile or bullet readily adaptable for firing from a number of different kinds of weapons including hand-held and shoulder-fired varieties. The different bullet sections or parts separate on firing to form a wedge-shaped pattern that 40 is lethal for an extended range. Moreover, each of the bullet sections spins in the plane of the direction of movement, whereby it is gyroscopically stabilized with its momentum vector perpendicular to the line of flight.

As a further aspect of the subject invention, a multi-section bullet is provided in which the pattern achieved upon dispersal downrange can be controlled by modifying the rate of gyroscopic precession. Thus, the angle 45

of dispersion produced at the muzzle of the barrel (FIG. 6) will in turn produce a certain rate of gyroscopic precession effecting a corresponding pattern change.

5 Although the bullet elements 16 may be made in a conventional disc of uniform thickness throughout, it is advantageous to bevel the edges as in the described embodiments, not only to produce a gas seal as was described, but also to reduce aerodynamic drag during 10 flight.

What is claimed is:

1. A multi-section bullet and cartridge assembly, comprising:

a cartridge casing including a primer and propellant and having portions thereof defining an opening; a plurality of flat elements arranged in a face-to-face stack secured within the casing opening with the element edges facing outwardly of the opening; and said casing portions defining the opening being formed into at least one line of crimp along one side only of the stack and interacting with said elements to impart a spin to said elements in a common direction as said elements leave said casing.

2. A multi-section bullet and casing assembly, comprising:

a casing having portions terminating in an opening; and

a plurality of bullet sections each clampingly received within said casing opening at one side only such that on firing said bullet sections are each gyroscopically stabilized during flight with the momentum vector of each being substantially perpendicular to the line of flight and in the same direction.

3. A multi-section bullet and casing assembly, comprising:

a casing including a primer and propellant and having portions thereof defining an opening;

a plurality of tooth-edged disclike elements of substantially identical geometry stackingly received within said casing opening with the element edges facing outwardly of said casing opening; and said casing portions defining the opening including at least one crimp line extending along one side of the stack of elements and engaging the toothed edges thereof such that on firing spin is imparted to each element.
